UNITED STATES PATENT OFFICE.

WILLIAM H. FRATER, OF DETROIT, MICHIGAN, ASSIGNOR TO AMERICAN AUTOPARTS COMPANY, OF DETROIT, MICHIGAN, A CORPORATION.

ADJUSTABLE FORM FOR SHAPING ARTICLES.

Application filed July 18, 1923. Serial No. 652,264.

This invention relates to a new and improved adjustable form for shaping material and more specifically to an apparatus particularly adapted for forming curved 5 springs or similar articles.

Articles such as springs are formed by being pressed to the desired shape while heated to a proper temperature and are then quenched while maintained in the desired shape. When so treated and properly 10 quenched they maintain the desired contour upon being released from the form. Springs of this character are used formed to a wide variety of contours. It is consequently customary to provide adjustable shaping means 15 which may be adapted to form the various shapes desired.

It is obviously necessary for practical and efficient operation of such shapers that the 20 forms engaging the material are such as to permit adequate contact of the spring being formed with the quenching fluid. Where, as is customary, the springs are formed upon circular arcs, the changing of the adjustment 25 of the forming elements from one arc to another is a lengthy operation requiring great care since each form element must be adjusted an amount differing from the adjacent elements.

It is an object of the present invention 30 to provide a new and improved apparatus for forming curved articles comprising a form consisting of a plurality of relatively adjustable elements together with means for simultaneously adjusting the elements.

It is a further object to provide an apparatus of this character in which the elements throughout their range of adjustment 40 may be maintained in predetermined geometric relation.

It is an additional object to provide an apparatus of this character consisting of 45 movable cams adapted for simultaneous operation, the cams engaging the various elements differing in contour whereby the elements may be simultaneously differentially adjusted.

It is an additional object to provide means of this character in which the forming 50 elements are yieldingly maintained in engagement with the adjusting means.

It is a further object to provide an apparatus having the forming means divided

into a plurality of series, each of which may be adjusted independently, while the 55 elements of each series may be maintained in predetermined relation.

Other and further objects will appear as the description proceeds.

I have illustrated a preferred embodiment of my invention in the accompanying drawings, in which—

Figure 1 is a plan view of an apparatus embodying the present invention;

Fig. 2 is a section taken on line 2—2 of 65 Fig. 1; and

Fig. 3 is a side elevation of the apparatus, certain parts being broken away for the sake of clearness.

The apparatus comprises the tank 11 70 which is adapted to contain the oil quenching bath, this tank being provided with the bearings 12 into which are fitted the trunnions 13 of the main frame 14. This main frame 14 carries the sliding frame 15 which 75 is fitted in the guide-ways 16. This frame 15 is maintained at one limit of its movement, as shown in Fig. 1, by springs 17. The frame 15 has adjustably secured thereto by bolts 18, the spring members 19 which support the flexible spring-forming member 20.

The frame 15 is slid longitudinally of the main frame 14 against the resistance of the 80 springs 17 by means of the arms 21 pivoted to frame 16 at 22 and having the rollers 23 engaging the edge 24 of the frame. At the inner limit of its movement the rollers 23 fit in depressions 25 and the frame is maintained in this position against the resistance 85 of the springs 17.

The main frame 14 has the cross member 26 upon which are supported a plurality of forming elements 27. These elements are held down by the removable plate 28. The forming elements as shown in Figs. 2 and 3 carry the pins 29 which are adapted to contact with the material to be formed. These pins are secured in place by bolts 30 and to the upper ends of these bolts are secured the springs 31, the opposite ends of which are secured to studs 32 carried by plate 28.

As best shown in Fig. 2, each element 27 carries an adjustable contact stud 33 105 which is threaded in an opening 34 in the

element and is locked in adjusted position by nut 35. These contact studs each contact with a rotary cam 36 carried by shaft 37 or 38, these shafts being supported in alined relation upon the main frame 14. The shaft 37 is provided with the gear 39 with which meshes the pinion 40, the pinion 40 being provided with an operating shaft having a squared end 41. The shaft 38 is provided with a similar gear 42 meshing with pinion 43 which may be operated by squared shaft 44.

In the operation of the apparatus, the blank to be formed is first heated to the proper temperature and then is placed against the pins 29. The levers 22 are swung to force the member 20 against the blank and this member being flexible causes the blank to conform to the arcuate contour defined by the closely spaced pins. The entire frame 14 and its associated parts are now swung from the horizontal position in which they are shown in Fig. 1 to the vertical position. This serves to carry the heated and curved blank below the level of a quenching bath of oil in the tank 11. It will be understood that the frame 14 is provided with suitable counterbalances and latches for maintaining it in the desired position and facilitating its movement. These features form no part of the present invention and have not been shown and need not be described in detail. When the blank is adequately quenched, the frame and associated parts are returned to the horizontal and the blank which now maintains its curvature is removed from the pins of the contact elements by releasing the sliding frame 15 which is drawn to the position of Fig. 1 by springs 17.

The cam surfaces upon the cam wheels 36 are so related that in whatever position the shaft 37 or 38 may be turned, all of the elements associated with cams carried by the shaft will maintain their contact pins upon the arc of a circle. The radius of this circle obviously varies as the shaft is turned. When turned to one limit of movement, the radius of the circle will reach infinity and the pins will be upon a straight line. The opposite limit of adjustment may be such as to bring the pins to an arc of relatively small radius such, for example, as twenty-four inches.

Each of the forming elements may be adjusted individually relative to its associated cam wheel by loosening the corresponding lock nut 35 and turning the contact stud 33. Proper adjustment may be determined by rotating the shaft to bring the elements to their limit of movement at which they should be upon a straight line. The elements may then be tested by a straight edge and the proper studs varied to bring them all into contact with the straight edge.

It is sometimes desirable to form springs having their two ends formed upon arcs having differing radii of curvature. Therefore, the two series of elements are associated with separate actuating shafts so that each series may be operated independently of the other. It is apparent, of course, that if a continuous arc is desired, the two shafts may be adjusted to the same rotary position.

This apparatus is capable of rapid adjustment to an infinite variety of circular arcs. While throughout the present discussion reference has only been made to circular arcs, it will be apparent that the cam surfaces may be so formed as to simultaneously adjust the various forming elements to provide any desired relationship between the elements through their range of adjustment.

I have illustrated one preferred embodiment of my invention but I contemplate such changes and modifications as come within the scope of the appended claims.

I claim:

1. Apparatus for forming curved articles comprising a form consisting of a plurality of relatively adjustable elements, rotary cams engaging the elements, a shaft carrying the cams whereby they may be rotated to simultaneously adjust the elements, and means for forcing the article against the adjusted form elements. 90

2. Apparatus for forming curved articles comprising a form consisting of a plurality of relatively adjustable elements, rotary cams engaging the elements, a shaft carrying the cams whereby they may be rotated to simultaneously adjust the elements, the cam surfaces being so related that the elements are maintained in predetermined geometric 95 relation, and means for forcing the article against the adjusted form elements. 100

3. Apparatus for forming curved articles comprising a form consisting of a plurality of relatively adjustable elements, rotary 110 cams engaging the elements, a shaft carrying the cams whereby they may be rotated to simultaneously adjust the elements, means whereby the elements may be individually 115 adjusted relative to the cams, and means for forcing the article against the adjusted form elements.

4. Apparatus for forming curved articles comprising a form consisting of a plurality of relatively adjustable elements, means for simultaneously adjusting said elements, means for maintaining the form elements 120 yieldingly in engagement with the adjusting means, and means for forcing the article against the adjusted form elements. 125

5. Apparatus for forming curved articles comprising a form consisting of a plurality of relatively adjustable elements, rotary cams engaging the elements, a shaft carrying the cams whereby they may be rotated to 130

simultaneously adjust the elements, and spring means maintaining the elements in engagement with the cams.

engaging each series of elements whereby the elements of each series may be adjusted independently of those of other series.

10

Signed at Detroit, Michigan, this 13th day of July, 1923.

WILLIAM H. FRATER.

6. Apparatus for forming curved articles comprising a plurality of series of relatively adjustable elements, rotary cams engaging the elements and a shaft carrying the cams
